WRENCH FOR REMOVING SCREW TOPS
FROM JARS

Walter W. Edlund, Burlington, Vt.

Application June 21, 1946, Serial No. 678,191

1 Claim. (Cl. 81—342)

1

This invention relates to screw top removers for jars, bottles, etc.

It is an object of this invention to provide a novel device having relatively movable jaws slidably propelled toward each other by spring means mounted on said device.

It is a further object of this invention to provide an improvement on device disclosed in Patent No. 1,894,556 granted January 17, 1933 to Henry J. Edlund. I have discovered that means should be provided whereby in this prior structure the clamping jaws are caused to automatically grip the closure initially and thereby automatically retain it on the screw top.

It is an object of this invention to prevent accidental displacement of my improved device from its initial application to a closure as well as assist in the function of gripping the closure while it is being unscrewed.

It is also an object of this invention to provide an automatic means to maintain the sliding jaw members with their jaws in their closest approach to each other when not in use and thereby holding the parts in compact position which prevents their rattling thus rendering the instrument more silent and preventing undue wear thereof.

Other objects and advantages will be revealed in the detailed description of the accompanying drawings which constitute a part of this specification.

In the drawings:

Figure 1 is a longitudinal sectional view of my improved device showing it as applied to a jar closure.

Figure 2 is a transverse sectional view taken centrally thereof in a vertical plane.

Figure 3 is an elevational view of my device as seen when looking directly at the bottom thereof when in a partly open condition.

Figure 4 is an elevational view of one of the sliding jaw members including its jaw when looking directly at the bottom thereof.

The drawings are merely illustrative of a preferred form of my improvement and are not to be construed as definitive of my improved invention except as claimed herein.

The reference characters in both the drawings and the specification merely identify the particular parts and portions shown and described.

In my screw top remover for jars the body 1 is provided with longitudinal channel means 2 and 2' having their open sides facing each other. This channel means constitutes parallel guides for reciprocally mounted U-shaped jaw members 55

2

3 and 4. The legs of the U-members are received and guided by the channel means 2 and 2'. One leg 5 and one leg 6 of which are respectively provided with gear teeth 7 and 8 defining racks arranged in opposed parallel relation to each other. A pinion 9 is interposed between the racks and intermeshes with said rack teeth.

The pinion 9 is fixed on the lower end of an upright shaft 10 which is suitably journaled in the body 1. The upper end of the shaft 10 has fixed thereon a transversely extending handle 11. The latter is provided with a recess receiving the upper end of the shaft 10 and is secured thereon by a pin or rivet 12 passing through both said handle and said shaft.

Each U-shaped member is provided with a depending jaw 13 or 14 adapted to engage a closure 15 which may be interposed between said jaws.

In order to urge the jaws automatically toward each other I have shown, in my preferred form, a helical spring 16 having its upper end anchored in the upper portion of the shaft 10 and its lower end anchored in the body 1, as clearly shown in Fig. 1.

25 The spring 16 is mounted and anchored under tension so that the coils of the helix are under a clockwise tension at all times.

When it is desired to set the wrench in operative position the handle 11 is grasped by the fingers of one hand and, if the screw cap closure is not overly large, the body 1 may be rotated by pressure of the thumb in a counter-clockwise direction to open the jaws sufficiently to receive the cap. Release of the thumb causes the body 30 to rotate in the opposite direction under the influence of the spring so that the jaws automatically grip the edges of the jar closure. In instances where the closures are comparatively large in diameter the handle may be gripped in the fingers of one hand and the body rotated to the limit of its movement by the other hand where it will be held by engagement therewith of the thumb of the hand which is grasping the handle. Then upon placement of the body over 35 the jar cap release of the thumb permits the jaws to be closed by spring pressure.

It will be seen from the above that the engagement of the jaws is automatic and the provision of the spring obviates the necessity of holding the body 1 stationary with one hand while the handle 11 is rotated by the other to cause the jaws to grip the cap. This is an important feature of operation in that many jar caps have a smooth periphery and even if these are roughened slightly it is necessary before a

cap can be loosened that the body be held until rotation of the handle 11 is sufficiently powerful to cause the jaws of the wrench to bite into opposite sides of the cap. In accomplishing this initial grasp of the jaws the spring 16 is a substantial aid in facilitating the removal of jar caps. In order to unscrew the closure the handle 11 and shaft 10 must by force be rotated in a counter-clockwise direction. It will be noted that the greater the counter-clockwise torque of the handle, shaft and pinion 9 the greater will be the grip of the jaws on the interposed closure.

Not only does the spring maintain my device on the closure to prevent accidental displacement, but it also aids in producing the counter-clockwise torque.

Of course, the receptacle having the screw cap or closure which is to be removed, must be held against rotation by some means such as a suitable clamp (not shown) or it may be held against rotation by the user or an assistant who may be available.

Having fully disclosed my improved invention what I claim is:

The combination with a hand wrench for 25 manually removing screw tops from jars com-

prising a supporting body carrying a rack and pinion mechanism provided with gripping jaws and a shaft fixed to the pinion and journaled on the body and a hand grasping handle fixed to the shaft, of a coil spring surrounding the shaft and anchored at its ends to the body and shaft, said spring being under initial tension to normally effect rotation of the body in one direction on the shaft as the wrench is held by the handle in the hand of the operator and also serving to move the jaws toward each other when the body has been rotated in the opposite direction and subsequently released while the handle is so held.

WALTER W. EDLUND.
